[57] CLAIM

The ornamental design for a coffeemaker or the like,
substantially as shown.

DESCRIPTION

FIG. 1 is a front isometric view of the coffeemaker or
the like showing our new design;

FIG. 2 is a front elevational view;

FIG. 3 is a rear elevational view;

FIG. 4 is a left side elevational view;

FIG. 5 is a right side elevational view;

FIG. 6 is a top plan view; and

FIG. 7 is a bottom plan view.

*FIG. 1**FIG. 2**FIG. 3**FIG. 4**FIG. 6**FIG. 7**FIG. 5*
